(57) **CLAIM**

The ornamental design for a vehicle wheel front face, as shown and described.

DESCRIPTION

FIG. 1 is a perspective view of a vehicle wheel front face according to one arrangement of the present design.

FIG. 2 is a front view of the vehicle wheel front face shown in FIG. 1.

FIG. 3 is a perspective view of a second embodiment of a vehicle wheel front face according to the present design; and,

FIG. 4 is a front view of the vehicle wheel front face shown in FIG. 3.

The broken lines shown herein are for illustrative purposes only and form no part of the claimed design.
